T. J. COO.

TYPE WRITING MACHINE.

APPLICATION FILED SEPT. 17, 1912.

1,117,793.

Patented Nov. 17, 1914.

UNITED STATES PATENT OFFICE.

THOMAS J. COO, OF TORONTO, ONTARIO, CANADA, ASSIGNOR TO UNDERWOOD TYPE-WRITER COMPANY, OF NEW YORK, N. Y., A CORPORATION OF NEW YORK.

TYPE-WRITING MACHINE.

1,117,793

Specification of Letters Patent.

Patented Nov. 17, 1914.

Application filed September 17, 1912. Serial No. 720,755.

To all whom it may concern:

Be it known that I, THOMAS J. COO, a subject of the King of Great Britain, residing in the city of Toronto, Province of Ontario, Dominion of Canada, have invented certain new and useful Improvements in Type-Writing Machines, of which the following is a specification.

This invention relates to typewriting machines having divided platens, and has especial reference to the means for rotating the platen sections.

In typewriting machines of the divided platen type, one section of the platen is usually used for holding a bill sheet and the other for holding a ledger leaf. When the bill is written, certain data are transferred to the ledger leaf and then the platen section carrying the bill sheet is actuated to eject the bill and introduce another bill in its place.

In the present invention means are preferably provided, adjacent to the actuating means for the platen section carrying the bill sheet, for quickly actuating the second platen section to quickly introduce, feed, or eject the ledger sheet. These two actuating means are arranged compactly and disposed so that they can be readily operated separately or simultaneously with one hand or finger of the operator. Thus the bill sheet and ledger sheet can be introduced simultaneously into the machine and together quickly moved for the major portion of the space necessary to adjust the sheets to the proper position for writing. The bill may then be written, the data transferred to the ledger sheet, and then both can be ejected simultaneously. If several bills are to be written to the same party, one of the quick actuating devices may be operated for introducing and ejecting the bills, and when the last bill has been written, both of the quick actuating devices may be operated simultaneously to eject both the bill and the ledger leaf. This results in a considerable saving of time, as two distinct operations can be performed separately or simultaneously with little effort or thought on the part of the operator.

In the preferred form of the invention, on the stub lever which carries the pawl engaging the ratchet of the platen section used for the bill sheets, I mount an additional pawl on the other side thereof to engage a ratchet

wheel connected to the ledger platen section. The stub lever is thus mounted between two ratchet wheels, either one of which or both may be engaged by the pawls on the stub lever. One of the pawls has a handle which projects outwardly longitudinally thereof, and the other pawl is shorter than the first pawl and has a handle projecting laterally thereof. Either one of these handles may thus be easily picked out and grasped by the operator to actuate the desired platen section, whereas, if it is desired to actuate both platen sections simultaneously, both handles may be readily grasped and operated together.

Other features and advantages will hereinafter appear.

In the accompanying drawings, Figure 1 is a plan view partly in section of a divided platen with my improved actuating means mounted on the platen axle. Fig. 2 is a perspective view of the improved construction, one of the platen sections being detached for the sake of clearness. Figs. 3, 4 and 5 illustrate sections taken respectively along lines 3-3, 4-4 and 5-5 of Fig. 1 looking in the direction of the arrows.

The platen axle 1 has at its ends usual platen turning knobs 2 and the paper feed ratchet 3 connected thereto. The platen 85 comprises two separately rotatable sections 4 and 5. The platen section 4 is fast on a tubular shaft 4^a extending the length of the axle between its bearings in the carriage, while the platen section 5 is loose and has 90 fast thereto at its outer end the finger wheel 6, whereby it may be rotated by hand. Mounted on the axle, at the end opposite to that carrying the paper feed ratchet are means which may quickly rotate the first 95 platen section 4 to introduce or eject a bill or some such paper on which little writing is done in proportion to its size. These means consist of a lever 7 carrying a pawl 8 engaging a ratchet wheel 9 connected to 100 the platen axle. This lever is mounted on a stub lever 10 which is loose upon the axle and the pawl 8 is normally kept out of engagement with the ratchet by a spring 11 fixed to the stub lever and bearing against 105 the lever 7 to hold the same against a lug 12 formed on the stub lever.

The loose platen section may be used for holding a ledger leaf or some such paper upon which data is transferred, and in order 110

that this platen section may also be quickly rotated independently of the first section or simultaneously therewith, I mount on the opposite side of the stub lever another lever 13 carrying a pawl 14 to engage a ratchet wheel 15 fast on the loose platen section. This lever 13 extends farther forward than lever 7 and has preferably an elongated finger piece 16 which can be readily grasped and distinguished by touch from the handle 17 of lever 7. The latter handle extends laterally and can also be readily grasped and distinguished from the handle on the other lever. When it is desired to actuate both platens simultaneously, both levers 7 and 13 may be grasped together and both ratchet wheels 9 and 15 may be rotated at one and the same time to actuate their respective platen sections.

20 A spring 18 may be provided also for lever 13 to hold it normally against lug 19 on the stub lever out of engagement with the ratchet wheel 15. The ratchet wheels are provided with shoulders 20 and 21 which 25 abut the stub lever and hold the same clear of the ratchet teeth.

A detent 22 may also be supplied for the ratchet wheel 15 to hold the corresponding platen section in proper line spacing position. The other platen section may be provided with the usual detent (not shown) to engage the paper feed ratchet 3, and said ratchet wheel may be engaged by the usual line space pawl 23 which is operated by the ordinary carriage return handle, not shown. The platen and its appurtenances are journaled in the usual bearings 24, 25 adjacent the end wheels 2, and the sleeve 4^a carrying the section 4 of the platen extends substantially from one bearing to the other.

40 A shoulder 26 on said platen section 4 is arranged to form a journal for the platen section 5. Said section 5 preferably is formed with a metal collar 27 having a flange 28, which collar bears against the shoulder and face of said section 4, and obtains a wide bearing thereon.

The opposite end of said section 5 adjacent the line space wheel 15 carries a collar 28, which bears on the sleeve 4^a. Thus it will be seen that the sleeve 4^a, which is of considerable diameter and has great stiffness, will properly support the center where the two sections of the platen may join, and 55 will carry the load of said platens out to the end of the axle adjacent the bearings 24 and 25. In this way, liability of spreading occurring at the joint where the section 4 meets section 5 is avoided.

60 The construction above described is very simple, compact and efficient. The arrangement of both ratchet actuating levers on the same stub lever reduces the number of parts, and saves in material and space. By reason 65 of the arrangement and proportioning of

levers and handles the actuating means for each platen section may be easily picked out with a minimum of mental effort, and when it is desired to actuate both platens simultaneously it may be accomplished with the use of one hand operating with similar ease both of the above actuating means together.

Variations may be resorted to within the scope of the invention, and portions of the improvements may be used without others.

Having thus described my invention, I claim:

1. The combination with a divided platen comprising an axle, a platen section attached thereto, and a second platen section rotatably mounted on said axle, of a ratchet wheel connected to said axle, a second ratchet wheel connected to said second platen section, a lever rotatably mounted between said ratchet wheels, a pawl mounted on each side of said lever, and handles connected to said pawls and projecting different distances beyond said lever.

2. The combination with a divided platen comprising an axle, a platen section attached thereto, and a second platen section rotatably mounted on said axle, of a ratchet wheel connected to said axle, a second ratchet wheel connected to said second platen section, a lever journaled between said ratchet wheels, and a pawl mounted on each side of said lever, one of said pawls having a longitudinally projecting handle and the other of said pawls having a laterally projecting handle.

3. The combination with a divided platen comprising an axle, a platen section attached thereto, and a second platen section rotatably mounted on said axle, of a ratchet wheel connected to said axle, a second ratchet wheel connected to said second platen section, a stub lever journaled between said wheels, levers pivoted on each side of said stub lever and having teeth adapted to engage the respective ratchet wheels, and springs carried by said stub lever holding said toothed levers out of engagement with the ratchets.

4. The combination with a divided platen comprising an axle, a platen section attached thereto, and a section platen section rotatably mounted on said axle, of a ratchet wheel connected to said axle, a second ratchet wheel connected to said second platen section, a lever mounted between said ratchet wheels, the ratchet wheels having shoulders engaging the lever, and pawls mounted on each side of said lever to engage said ratchet wheels.

5. In a typewriting machine, the combination with a platen axle having bearings adjacent the ends thereof, of a sleeve on said axle, a bill section fast to said sleeve, a journal formed as an extension of said sec-

tion, a ledger section having a bearing on said journal at one end and a bearing on said sleeve adjacent the end bearing of the platen axle at the other end, and a hand wheel connected to each section for turning the sections separately.

6. In a typewriting machine, the combination with a platen axle journaled at its ends, of a sleeve supported throughout its length on the axle, a platen section fast on said sleeve, an extension of said section forming a journal, and a second platen section having a bearing on said first section and a bearing on said sleeve.

15. 7. The combination with a platen comprising two sections rotatable relatively to each other, of devices operable as a unit for rotating said sections simultaneously from adjacent points and at the same speed, said devices also operable separately to rotate each platen section independently of the other.

8. The combination with a divided platen comprising two sections rotatable relatively to each other, of a ratchet wheel connected to each section, and devices for independently operating said ratchet wheels, said devices located for simultaneous actuation by one hand or finger of the operator.

30. 9. The combination with a platen comprising two sections rotatable relatively to each other, of mechanism for rotating said sections comprising actuating means for each of said sections arranged to enable an operator to quickly actuate them by one hand either separately or simultaneously.

10. The combination with a platen comprising two sections rotatable relatively to each other, of mechanism for rotating said sections comprising actuating means for each of said sections arranged to enable an operator to actuate them either separately or simultaneously as a unit from adjacent points.

45. 11. The combination with a platen axle and a platen section fast to the axle, of a section rotatable on said axle, line-space mechanism arranged to turn one section, and levers adjacent each other arranged to be operable by one hand of the operator either separately to turn said sections separately or together as a unit to turn both of said sections simultaneously.

12. The combination of relatively rotatable platen sections, a ratchet wheel connected to each section, a lever pivoted concentrically with the ratchet wheels, and pawls mounted on said lever and independently movable into engagement with the ratchet wheels.

50. 13. The combination with a platen comprising a platen axle, a section fixed thereto, and a section rotatable on said axle, of ratchet wheels connected respectively to said sections and rotatable about the platen axis, a

lever, pawls thereon selectively movable each independently of the other into engagement with said ratchet wheels, and means connected to said pawls for moving them into engagement with the ratchet wheels 70 either singly or together and rotating said lever whereby the platen sections may be rotated either selectively or simultaneously.

14. In combination, a platen comprising relatively rotatable sections, an operating 75 lever, and means carried by the lever for connecting the same to either of the platen sections singly or to both the platen sections at once, thereby permitting either a selective or simultaneous rotation of said sections.

15. The combination with a divided platen comprising an axle, a platen section attached thereto, and a second platen section rotatably mounted on said axle, of a ratchet 85 wheel connected to said axle, a second ratchet wheel connected to said second platen section, a swinging pawl carrier, and pawls thereon arranged for simultaneous actuation by one hand of the operator for 90 operating said ratchet wheel simultaneously, each pawl also operable to rotate its ratchet wheel and connected platen section independently of the other platen section, and while the other pawl remains inoperative. 95

16. The combination with a divided platen comprising an axle, a platen section attached thereto, and a second platen section rotatably mounted on said axle, of a ratchet wheel connected to said axle, a second 100 ratchet wheel connected to said second platen section, a lever rotatably mounted between said ratchet wheels, a pawl mounted on each side of said lever, said pawls movable either singly or together into engagement with 105 said ratchet wheels, whereby either platen section may be rotated independently of the other, or both sections may be rotated together at the same speed, and means for operating the pawls.

17. The combination with a divided platen comprising an axle, a platen section attached thereto, and a second platen section rotatably mounted on said axle, of a ratchet wheel connected to said axle, a second 115 ratchet wheel connected to said second platen section, a lever pivoted co-axially with the platen, and pawls mounted one on each side of said lever on a common fulcrum pin, one of said pawls having a laterally extending handle and the other of said pawls extending beyond said first pawl and having a longitudinally extending handle, whereby the pawls may be operated either together to rotate the platen sections together and at 120 the same speed, or either platen section may be rotated independently of the other.

18. In a typewriting machine, the combination with a platen comprising independently rotatable sections having a com- 130

4
mon axis of rotation, of line-space mechanism for rotating one section, a ratchet wheel on each section, pawls to separately engage said ratchet wheels for rotating said sections independently of the line-space mechanism, and a swinging member carrying said pawls, said pawls provided with finger-pieces located adjacent each other to permit either pawl to be actuated independ-

ently of the other, or both pawls to be actuated simultaneously by one hand or finger of the operator, whereby the platen sections may be rotated either independently of each other or together as a unit. 10

Witnesses:

D. S. TONELL,
R. S. CHILTON.

It is hereby certified that the State of incorporation of the assignee in Letters Patent No. 1,117,793, granted November 17, 1914, upon the application of Thomas J. Coo, of Toronto, Ontario, Canada, for an improvement in "Type-Writing Machines," was erroneously given as "New York," whereas said State should have been given as *Delaware*, as shown by the records of assignments in this office; and that the said Letters Patent should be read with this correction therein that the same may conform to the record of the case in the Patent Office.

Signed and sealed this 15th day of December, A. D., 1914.

J. T. NEWTON,

Acting Commissioner of Patents.

[SEAL.]
